UNITED STATES PATENT OFFICE.

LEO DAFT, OF GREENVILLE, NEW JERSEY.

ELECTRIC-ARC LAMP.

SPECIFICATION forming part of Letters Patent No. 276,566, dated May 1, 1883.

Application filed September 6, 1882. (No model.)

To all whom it may concern:

Be it known that I, LEO DAFT, a citizen of Great Britain, now residing at Greenville, in the State of New Jersey, have invented a new 5 and useful Improvement in Electric Lamps or Regulators, of which the following is a full, true, and exact description, reference being had to the accompanying drawings.

My invention relates to an improvement in 10 electric lamps or regulators, by means of which the hollow coil and axial magnet are dispensed with, and an ordinary **U**-magnet of a peculiar shape having a fixed core substituted therefor.

In my improved lamp the vertical movement 15 of the carbon is accomplished by means of an armature which is laterally attracted toward a fixed magnet, said armature being itself preferably polarized and made of opposite polarity to that of the attracting-pole of the magnet.

20 My invention will be readily understood from the accompanying drawings, in which Figure 1 represents an elevation, and Fig. 2 a plan view.

Similar letters refer to similar parts.

The whole details of the lamp are not given, 25 but merely the working parts of my improvement.

30 **A** represents the frame of the lamp, suitably supported and arranged; **B**, the carbon-holder; **C** **D**, coils of a **U**-magnet, the poles being turned toward each other, as shown. The rear ends are connected by the yoke **F**, which makes a magnetic connection between the cores of the coils **C** **D**, thereby increasing the attractive 35 force. The coils **C** **D**, as usual, are so wound as to produce opposite polarities in their cores.

Attached to the core of the spool **C** is the 40 vibrating armature **G**, which is arranged to lift the carbon-holder. This armature is pivoted to the core of the coil **C** and magnetically connected therewith. It surrounds the carbon-holder **B**, where it is enlarged into a ring, as shown at **H**. The inner end of the core of the coil **D** is preferably curved, so as to correspond with the arc swept by the free end of **G** as it is elevated, and the said free end of **G** may be correspondingly curved, as shown in Fig. 1. The coil **D** and its core are made vertically adjustable in the support by means of the screw **L**, thereby determining the length of the arc 45 of the lamp. The coil **D** is surrounded by the auxiliary or differential coil **E**, which may be

used, when required, in the well-known way. The clutch of the carbon-holder is of the form heretofore described by me in an application filed on the 11th day of August, 1882. The links 55 **K** **K** are attached to the ends of levers which control cams bearing against the carbon-holder **B**, which cams are supported in a frame, **M**. As the armature **G** is elevated the cams are turned in against the carbon-holder, which therefore rises with the armature, while when the armature **G** drops, the lever ends are dropped, the eccentrics or cams thrown away from the carbon-holder, and the carbon-holder falls. The links **K** **K** are pivoted opposite each other on 60 a line passing through the center of the carbon-holder **B**, at right angles to the movement of the armature, thereby giving an equal movement to both cams.

The operation of this lamp will be readily 70 understood. As soon as the electric current flows through the coils **C** **D**, which are of course connected in circuit, as usual, the end of the armature **G** and the inner end of the core of the coil **D** will possess opposite polarities, and 75 said free end will consequently be immediately raised. As it is elevated the clutch on the carbon-holder is operated and the carbon-holder is raised, establishing the arc. The length of this arc is determined by the adjusting-screw **L** in the manner previously described. The arc, if extinguished, is re-established by the dropping of the carbon-holder **B** in the manner previously described.

I do not limit myself to the precise arrangement shown, as other modifications will readily suggest themselves.

What I claim as my invention, and desire to secure by Letters Patent, is—

1. An electric-lamp regulator which consists 90 of a carbon-holder, a polarized armature pivoted at one end at one side of the carbon-holder and crossing the latter, a magnet adjacent to the free end of the armature for raising the same, and magnetically connected with the pivot of the armature for polarizing the same, and a clutch connecting the armature and the carbon-holder, substantially as described.

2. The combination, in an electric-lamp regulator, of a carbon-holder and polarized armature pivoted so as to swing in a vertical plane, 95 a coil on the opposite side of the carbon-holder,

and facing and adapted to raise the free end of the armature, and a clutch for raising the carbon-holder, substantially as described.

3. The combination, in an electric-lamp regulator, of a vertically-moving polarized armature surrounding a carbon-holder, said armature being pivoted so as to swing in a vertical plane, and a magnet-coil past the pole of which said armature swings, said coil surrounding a core which is magnetically connected with the pivoted armature for the purpose of magnetizing the same, substantially as described.

4. The combination, in an electric-lamp regulator, of the free extension-armature G, coils

C, to which said armature is pivoted, polarizing the same, the stationary coil D, adapted to attract the free end of said armature G, the clutch, and the carbon-holder, substantially as described.

5. The combination of the carbon-holder B, the vertically-swinging pivoted armature G, the coil C, and the attracting-magnet D, itself made vertically adjustable, substantially as described.

LEO DAFT.
